TRIMMING ATTACHMENT FOR SEWING MACHINES

Arnold Krohn, Brockton, Mass.

Application September 17, 1940, Serial No. 357,106

13 Claims. (Cl. 112—127)

The main object of this invention is to provide a simple and effective trimmer for application to sewing machines for the purpose of trimming the edge of a piece of work while stitches are being formed and placed in the work. One important use for such a trimming device is to cut off the edges of the linings or inner facings of shoe uppers at the same time that such linings are stitched to those edges of the shoe upper which are exposed to view in the finished shoe. A lining or facing of leather is ordinarily provided at the margins of the upper, and the edges of the upper leather are folded inward and stitched to such lining on a line parallel to the fold. Such folding gives a finished character to the exposed edges of the upper. Commonly the lining is trimmed close to the seam and slightly within the finishing edge fold of the upper leather in order not to impair this finished appearance.

Trimmers have heretofore been provided for this purpose with capacity for being put out of action when their use is not required, and for locating the knife in a position where it will not interfere with the sewing of other seams in parts of an upper, or other work piece, where trimming is not required. The most commonly used trimming attachments of the prior art are more or less cumbersome and bulky and have parts projecting for such a distance laterally from the location of the needle as to make difficult the manipulation of such work as a shoe upper in the manner necessary for trimming the lining at all of the edges where trimming is needed. An important part of my object is to eliminate such defects and provide a trimmer and means for putting it into and out of action which is devoid of projections liable to interfere with the manipulation of the work. Another object is to provide a simpler means for operating the trimming knife and for putting the knife into and out of action at the will of the operator, than those heretofore known, and one which can be applied to existing commercial sewing machines with a minimum of difficulty and without deranging the stitch-forming and work-feeding instruments of the machine or the mechanisms by which such instruments are operated.

It is to be understood that the mention herein of one important use for my invention is not a limitation of the scope in which I claim patent protection; but that all uses which the device herein disclosed is capable of serving, and all equivalents of this particular disclosure are included within the protection hereby claimed.

The nature of the invention and the particu-

lars in which it exists can best be explained by the description of one concrete embodiment thereof with reference to the drawings in which such embodiment is shown.

5 In the drawings—
Figure 1 is a front elevation of a sewing machine in which the invention is applied.

Figure 2 is a similar view on a larger scale of the work-supporting post at the forward end of the machine, in and on which the trimmer and the means for putting it into and out of action are mounted.

Figure 3 is a plan view of the post and external parts mounted thereon shown in Figure 2.

10 Figures 4 and 5 are detail sectional views taken on the lines 4—4 and 5—5 respectively of Figure 2.

Figure 6 is a detail horizontal section taken on the line 6—6 of Figure 1.

20 Figure 7 is in part a side elevation of the work-supporting post and in part a vertical section taken on line 7—7 of Figure 2.

Figure 8 is a vertical section taken on line 8—8 of Figure 7, viewed in the direction of the 25 arrows, and showing the trimming knife in elevation.

Figure 9 is a large scale view of the parts shown in section in the upper portion of Figure 7, showing the trimming knife in action for cutting off the edge of a shoe upper lining.

Figure 10 is a view similar to Figure 9 showing the trimming knife out of action and located in a position where it is clear of any interference with a work piece supported on the post.

35 Fig. 11 is a perspective view of the trimming knife.

Like references indicate the same parts wherever they occur in all of the figures.

The front elevation of a standard sewing machine is illustrated in Figure 1. The reference number 11 represents the base supported on feet 12. A column 13 rises from the rear end of the base and supports an overhanging arm terminating in a head 14 in which the reciprocating needle bar 15 and presser bar 16 are mounted. A work-supporting post 17 rises from the base beneath the head 14 and contains a feed lever 18 (Figure 7) mounted to oscillate upon a pivot 19. In the present illustration said feed lever is substantially vertical and its pivot is substantially horizontal. Its upwardly extending arm carries a feeder plate 20 having a serrated upper edge projecting through a slot 21 in a work supporting plate 22 mounted on the upper end of the post. The upper surface of the plate 22,

whereon work is laid for stitching and trimming is substantially horizontal; and both this surface and the serrated edge of the feeder plate are sufficiently far removed from the pivot 19 to cause the feeding and return movements of the edge serrations to occur in a path of which the divergence from a substantially horizontal straight line is inappreciable. The presser bar 16 and presser foot 23, the needle bar 15, needle 24 and cooperating stitch-forming instruments, the feeder, and the mechanisms for operating these instruments are all standard parts of a commercial sewing machine and require no further illustration herein. The trimming apparatus in which the invention resides is independent of the details of such instruments and mechanisms, and may be employed in machines in which such instruments and mechanisms are of various characters.

A knife 25 is the trimmer or trimming instrument of this machine. It is provided with a cutting edge 26 adapted to reciprocate in a position crossing, and in contact with, the rear bounding edge 27 of the work supporting surface of plate 22. In the form shown here the knife is a bar of suitable material having its cutting edge provided on one end and having an integral lip 28 extending beyond and to one side of the cutting edge 26 in a location such as to hold the overlying piece away from the cutting edge while being stitched to an underlying piece and while the knife is trimming the edge of the under piece.

The knife is provided with a shank 29 of dovetail cross section; such shank being preferably formed by bending a portion of the knife bar at right angles to that portion on the end of which the cutting edge is located. One beveled face of shank 29 occupies an undercut guideway in a carrier block or holder 30, as shown in Fig. 4, and the opposite beveled face of the shank is engaged by a clamp 31 having a shank 33 which extends through the block and on which is threaded a nut 32 whereby the clamp may be set up against the shank. The holder 30 has an arm 34, of dovetail section offset from the above named guideway and extending in a direction substantially perpendicular to the shank 29 and parallel to that part of the knife which carries the cutting edge. Arm 34 is fitted in a horizontal guideway in the forward side and near the upper end, of a lever 35 to which it is secured adjustably by screws 36 passing into the lever through slots in the arm.

Lever 35 in turn is connected by a pivot pin 37 to a support 38 constructed as a slide which is fitted between parallel upright guiding surfaces 39 and 40 in the inner or rear face of the detachable front plate 41 of post 17. The axis of pivot 37 is parallel to the axis of pivot 19; in other words, is substantially horizontal, and is comparatively near the latter axis; as near as feasible to permit its up and down movement with the supporting slide 38 without interference. The levers 35 and 18 are substantially parallel and they oscillate in parallel planes about their respective pivots. Although the knife carrying lever 35 is in front of the feeder lever 18, the offset formation of the knife holder 30 brings the knife itself to a position in rear of the feeder plate 20 and against the rear edge of the work support. The knife is at such a distance from the pivot 31 that its reciprocating movements, through the short distance which suffices for trimming in machines in this char-

acter, are approximately straight and parallel to the upper surface or plane of the supporting plate 22, and parallel likewise to the movements of the feeder 20.

5 The manner in which the knife is connected to its carrier lever 35, by means of the intermediate holder 30, enables the knife edge to be adjusted to the proper height with respect to the work support and to the proper position with respect to the needle; and to be readjusted when its cutting edge recedes due to sharpening. The correct position of the cutting edge when the knife is in action, is beside the location of the needle; that is, approximately in a line from the 10 needle perpendicular to the direction of feeding impulses applied to the work; and the knife is reciprocated so that the cutting edge 26 moves back and forth across such perpendicular line in a path of which all points lie in a plane 15 parallel to the feed of the work.

Said cutting edge is preferably slanted at an acute angle to the overhanging lip 28 and extends substantially up to that lip. It cuts the work by virtue of relative movement between 20 the knife and work piece along the line of feed. Fig. 9 illustrates the manner of operation in trimming a shoe upper lining, for instance. There a represents a portion of a shoe upper, b a portion of the contiguous lining, and c the 25 edge fold of the upper. The folded edge is stitched to the lining by a seam d, and in the course of stitching the knife trims the lining at a distance from the seam determined by the 30 distance of the edge 27 and the knife from the 35 location of the needle. The separating lip 28 enters between the edge of the upper and the lining, holding the upper away from the cutting edge so that it is not marred and holding down the lining so that the latter is not raised by 40 the inclined cutting edge, but is properly cut.

Oscillating movement is imparted to the knife-carrying lever 35 by means of a driver consisting of a lever arm 42 and a coupling pin 43 carried by said arm and projecting into a slot 44 in the 45 arm 35a of the lever 35. The arm 42 is secured and keyed to one end of a rockshaft 45 which is mounted to turn in bearings 46 secured to the machine base 11 in the front of the post. An arm 47 is clamped about the rockshaft and extends downward through an opening in the base, having a fork 48 on its lower end which embraces a cam 49 on a cam shaft 50. Said shaft 50 is a standard part of the commercial sewing machine, and may be a part of the means by 55 which oscillating movement is given to the feed lever. Its other functions are immaterial to the explanation of the present invention. The only material fact is that an existing shaft of the commercial machine is utilized for imparting oscillating movement to the trimming knife.

The slide 38 may be raised and lowered. When raised, it places the trimming knife in the operative position shown in Figures 2, 3, 7, 8 and 9, in which the cutting edge of the knife crosses the plane of the work-supporting surface and rises a height above such plane substantially equal to the thickness of a work piece, such as the shoe upper lining b shown in Figure 9. When lowered, it coacts with other means previously described to place the knife in the inoperative position shown in Figures 1 and 10, in which the knife and its guard lip 28 are wholly below the supporting surface of the plate 22, or, at least, are depressed as far as not to interfere 70 with the work. A compression spring 51 secured 75

to the plate 41 by screw 52 enters a socket 53 in the slide 38 and tends constantly to depress the slide, being put under increased compression when the slide is raised. A second compression spring 530, confined at one end in a socket 54 in a portion of the slide 38, and at the other end in a socket 55 in the arm 35a of the knife-operating lever, tends constantly to move said lever from the full-line position to the dotted-line position shown in Figure 8, and thereby to retract the knife from its position abreast of the needle. That portion of the edge 27 of the supporting plate 22 which lies beside the retracted position of the knife (it is designated as 27a in Figure 3) is slightly inclined away from the path of the knife to permit unobstructed descent of the knife when so retracted, and to cause the knife edge to come into bearing with the parallel portion of the edge 27 when the knife is raised and advanced to cutting position.

To raise the slide 38 and permit its descent, I have provided a lifter 56; and to permit retraction of the knife by means of the spring 530 in the manner described, I have provided means for disengaging the pin 43 from the slot 44. Such disengagement is necessary also to prevent imparting of motion to the knife by the constantly vibrating arm 42 when stitching is performed without trimming. The pin 43 is slidingly mounted in a thimble 57 which is screwed into a tapped hole through the arm 42, and a spring 58 reacts between a wall or flange at the outer end of said thimble and a shoulder on the pin to advance or project the latter. The pin 43 has a trail rod 59 which passes through and projects from the end wall of the thimble 57 and is made fast to a head 60. A sleeve 61 is slidingly mounted on the thimble 57 between a shoulder 62 thereon and the head 60, and carries an upstanding projection 63 having a cam or wedge surface 64 (Figure 6) at the side adjacent to the post. Rotation of the sleeve is prevented, and the projection 63 is maintained in its upright position, by a guide bracket 65 secured to the arm 42 and projecting outwardly therefrom parallel to the axis of the thimble 57 in engagement with a flat surfaced projection 66 on the under part of the sleeve 61.

The lifter 56 is a cam disk pivoted on a stud 67 which is mounted in the front side of the plate 41 of the post and projects forward. The upper part of the periphery of the lifter disk has a cam portion 68 adapted to pass under and aside from a pin 69 which projects forwardly from the slide 38; the rise and descent of such cam being sufficient to bring the knife into the operative raised position and to permit its descent into the inoperative position. Adjacent to this cam surface the lifter has a supporting edge 70 of uniform radius in which there is a shallow notch 71 adapted to receive pin 69 and having a depth sufficient only to prevent the lifter from being shifted out of position by vibrations of the machine. An operating arm 72 is clamped around the hub 73 of the lifter.

The lower part of the lifter extends the side of the post and the projection 63 previously described, and carries in an adjustable manner a displacement cam 74 having a wedge surface 75. This latter is suitably located to pass into engagement with, and displace outwardly, the projection 63 when the lifter is turned counterclockwise from the position shown in Figure 2 to that shown in Figure 1 and the rise of wedge 75 is sufficient to withdraw pin 43 wholly from

engagement with the lever arm 35a. The cam surfaces 68 and 75 may be located to come into and out of engagement, one with the pin 69 and the other with the projection 63, simultaneously; but this is not an essential feature. It is only necessary that the cam 74 be wholly withdrawn from the projection 63 when the pin 69 is in the notch 71, and that the lifter be clear of this pin when the cam 74 is in retracting engagement with the projection 63. When the latter condition obtains, the knife is retracted and depressed by the joint action of spring 51, gravity, and spring 530.

In this condition, the slot 44 is at one side of the limits of oscillation of pin 43. In order to bring this slot within the range of the pin when the knife is raised by the cam 68 and the pin released from the restraint of cam 74, the lifter 56 is provided with a rearwardly projecting stud 76, and the lever 35a is provided with a forwardly projecting stud 77. These studs are at approximately equal distances from the axis of pivot 67, and otherwise so located that, when the lifter is turned clockwise from the position shown in Figure 1 to the broken line position shown in Figure 2, the stud 76 will engage the stud 77 and move the lever to the point where its slot 44 is within the limits of oscillation of the pin 43. Thus, to put the knife into action, the operator swings the arm 72 from the position of Fig. 1 to approximately the broken line position shown in Fig. 2, pauses until the pin springs into the slot, and turns back the arm until the pin 69 enters notch 71. In this position of the lifter, the stud 76 is clear of the stud 77.

When the knife is in operation, its cutting edge bears against the edge 27 of the work-supporting plate, whereby the latter edge cooperates with the cutting edge in obtaining a smooth clean cutting effect. This relationship is in part effected by the disposition of the knife-carrying lever and is reinforced by forward pressure exerted by the feeder plate 20 on the knife carrying lever 35 through a stud 78 which is secured to the lever 35 and bears at its rear end against the forward side of the feeder plate. Said stud is not secured to the feeder plate but bears slidably thereon, whereby both the lever and the feeder plate are free to move in their prescribed planes independently of one another.

This trimming mechanism gives cutting and return movements to the knife in a path parallel to the direction in which feeding impulses are applied to the work. The cutting motion is therefore in effect a straight line movement, for the arc of movement around the pivot 37 is of no effect, being in a plane perpendicular to the work. Such straight line movement, and the location of the cutting path directly beside the position of the needle, ensures continuity of successive cuts, whereby the resultant trimmed edge (whether straight, convex or concave) is substantially smooth and continuous, with no distinct jagged points or serrations. When the knife is made inoperative, it is put out of the way where it offers no impediment whatever to the placing of stitches in work at any distance from the edges of the work. The means for putting the trimmer into and out of action are efficient, easily and instantaneously operated, and are entirely clear of the work.

I claim:

1. In a sewing machine having a base and an upright post adapted to support work on its up-

per end, a lever support guided to move up and down on a portion of the post, a lever pivoted to said support on a substantially horizontal axis having a knife-carrying arm extending toward the plane of the work-supporting end of the post, a knife having a cutting edge transverse to said plane mounted on the extremity of said lever arm in a position adapting it to be shifted, by movement of the lever support, between positions in which it is, respectively, wholly below said plane and where its cutting edge crosses said plane.

2. In a sewing machine having a base and an upright post adapted to support work on its upper end, a lever support guided to move up and down on a portion of the post, a lever pivoted to said support on a substantially horizontal axis having a knife-carrying arm extending toward the plane of the work-supporting end of the post, a knife having a cutting edge transverse to said plane mounted on the extremity of said lever arm in a position adapting it to be shifted, by movement of the support, between positions in which it is, respectively, wholly below said plane and where its cutting edge crosses said plane, and a lever support lifter pivoted on the post below the upper end thereof and engaged with said lever support for raising and lowering the same and the lever to put the knife into one or the other of the before-named positions.

3. In a sewing machine having a base and an upright post adapted to support work on its upper end, a lever support guided to move up and down on a portion of the post, a lever pivoted to said support on a substantially horizontal axis having a knife-carrying arm extending toward the plane of the work-supporting end of the post, a knife having a cutting edge transverse to said plane mounted on the extremity of said lever arm in a position adapting it to be shifted, by movement of the support, between positions in which it is, respectively, wholly below said plane and where its cutting edge crosses said plane, and a lever support lifter pivoted on the post below the upper end thereof and engaged with said lever support for raising and lowering the same and the lever to put the knife into one or the other of the before-named positions combined with disconnectible means for imparting vibrative movement to said lever; the lever support lifter having provisions for disconnecting said driving means from the lever when the knife is placed in inoperative position.

4. A sewing machine including a post, a work-supporting plate mounted on the upper end of the post having a straight edge at one side thereof, a lever pivoted below the upper end of the post having a rising arm movable in directions parallel to said edge, a knife carried by the upper end of said lever arm, disconnectible driving means for oscillating the lever, and correlated means for lowering said arm and disconnecting said driving mechanism, and for raising the arm and connecting the driving mechanism; said knife being located on the lever so that its cutting edge bears against the straight edge of said plate and crosses the plane of the supporting edge of the plate when the lever is raised, and the knife is wholly below said plane when the lever is lowered.

5. A trimming attachment for sewing machines, comprising a supporting structure, a lever support guided to move in a given path on said supporting structure, a lever pivoted to said support on an axis transverse to the direction

of movement of the lever support and having a knife-bearing arm projecting from its pivot in said direction, a trimming knife carried by said arm, and a lever support lifter having a cam portion engageable with a projection on the lever support and movable so as to cause shifting of the lever support in one direction or the opposite direction in its prescribed path.

6. A trimming attachment as set forth in claim 5, combined with a driver for vibrating said lever, a disconnectible coupling between the driver and lever, and means operated by said lever support lifter for disconnecting said coupling when the lever support is lowered and connecting it when the lever support is raised.

7. A trimming attachment as set forth in claim 5, combined with a vibrating driver for the lever, a disengageable coupling between the driver and lever consisting of a retractable pin carried by one of them entering a slot in the other, and a cam element carried by the lever support lifter arranged and operated to retract said pin from said slot when the lever is lowered.

8. In a sewing machine having a base and a post rising from the base, said post being constructed with a work supporting top member and a detachable front plate, a knife lever support in guided engagement with the inner side of said plate for movement up and down, a knife lever pivoted to said lever support on a substantially horizontal axis within the post extending toward said work supporting member, a knife carried by said lever having a cutting edge lying in a plane transverse to said work supporting member and being located for placement above and below the work supporting portion of said member by movement up and down of said lever support, and a lifter mounted on said front plate in accessible position for manipulation by an operator and having a lifting portion engageable with a part of said lever support for raising the latter from a lowered position.

9. In a sewing machine having a base and a post rising from the base, said post being constructed with a work supporting top member and a detachable front plate, a knife lever support in guided engagement with the inner side of said plate for movement up and down, a knife lever pivoted to said support on a substantially horizontal axis within the post extending toward said supporting member, a knife carried by said lever having a cutting edge lying in a plane transverse to said work supporting member and being located for placement above and below the work supporting portion of said member by movement up and down of said lever support, a driving arm independent of said lever, means for oscillating said driving arm, and a disconnectible coupling between said arm and lever arranged to transmit movement from the arm to the lever at a point separated from the pivot axis of the latter.

10. In a sewing machine having a base and a post rising from the base, said post being constructed with a work supporting top member and a detachable front plate, a knife lever support in guided engagement with the inner side of said plate for movement up and down, a knife lever pivoted to said support on a substantially horizontal axis within the post extending toward said supporting member, a knife carried by said lever having a cutting edge lying in a plane transverse to said work supporting member and being located for placement above and below the work supporting portion of said member by

movement up and down of said lever support, a driver for said lever movable back and forth in opposite directions, a disconnectible coupling between said lever and driver for transmitting movement from one to the other, and a lifter movable in opposite directions, said lifter having means for raising the knife lever support from a lowered position when moved in one direction and for disconnecting said coupling when moved in the opposite direction.

11. A sewing machine comprising a base, a post rising from said base having a work supporting plate on its upper end, an oscillative work feeder mounted in the post extending at its upper end through said plate for engagement with work resting thereon and being movable in a given path for feeding the work, a needle mounted to reciprocate in a path transverse to said plate beside the feeder, a knife lever pivotally supported in the post to swing in a plane parallel to the plane in which the feeder oscillates, a knife carried by said lever located at the opposite side of the needle path from the feeder, means for raising and lowering the pivotal support for said knife lever through a distance sufficient to place the knife edge across a work receiving space above the work support, and below such space, an oscillative driving arm rising from the base adjacent to the knife lever, a disengageable coupling between said arm and lever for transmitting movement from one to the other, and means associated with said raising means for causing disconnection of said coupling when the knife lever is lowered and connection of the coupling when the lever is raised.

12. In a sewing machine having a base, a post rising from said base having a work supporting plate at its top and a front wall, a knife lever support in guided engagement with the inner 40

- side of said wall for movement up and down, a knife lever in pivotal connection with said support having arms extending upward and downward from such connection, a knife secured to the upwardly extending arm having an edged portion extending through the work supporting plate, a lifter pivoted on the outer side of said plate having a cam portion shiftable beneath a forward projection of the lever support for raising and lowering the support when moved in opposite directions, an oscillative driving arm rising from the base adjacent to the downwardly extending arm of said lever, a retractable coupling pin carried by said arm extending into 15 impelling engagement with the lever arm, said lifter and pin having interacting wedge elements cooperatively arranged to retract the coupling pin from engagement with the knife lever when the lifter is turned to cause lowering of the lever support.
- 10 13. In a sewing machine having an upright post with a work supporting top member, a knife lever support mounted in said post with provision for up and down movement toward and away from said top member, a knife lever pivoted to said support on a substantially horizontal axis having an arm extending toward said top member, a knife having a shank secured to said arm and a substantially horizontal portion above the arm provided with a cutting edge at its extremity and a separating lip projecting beyond and laterally from said cutting edge, and means for oscillating said lever; the lever support being shiftable between positions, in one of which the 25 knife edge crosses and extends above the upper surface of said top member, and in the other of which the knife and its separating lip are mainly below the said surface.
- 20 30 35

ARNOLD KROHN.
